GILBERT W. GOODRIDGE, OF FAIRFIELD, CONNECTICUT, ASSIGNOR TO THE BRYANT ELECTRIC COMPANY, OF BRIDGEPORT, CONNECTICUT, A CORPORATION OF CONNECTICUT.

LAMP SOCKET.

Application filed June 29, 1927. Serial No. 202,330.

My invention relates to lamp sockets, and particularly to sockets of the miniature type.

The object of my invention is to reduce the cost of construction of sockets of this type.

5 In the accompanying drawing —

Fig. 1 is a vertical section through a socket in which my invention is embodied in one form, and showing the manner of applying the pigtail connections to the socket contacts;

10 and

Fig. 2 is a similar section showing the pigtails secured to the lamp contacts and both housed within an insulating casing.

It is customary in the manufacture of 15 miniature sockets, which are used extensively in the trade for Christmas tree "strings", to assemble upon an insulating button both screw shell and center contacts, and there-

20 after to connect the pig tail leads to these contacts by a suitable soldering operation.

My invention eliminates the usual center contact, as well as the expense of attaching it to the insulating button. I form the center contact incident to the soldering operation

25 by which one of the pigtails is connected to the socket.

I have indicated at 3 an insulating button which may be of any appropriate shape and material, and may be connected in any suitable fashion to the screw shell contact 4 for support. I prefer to mold the button 3 from glass in the bottom of the screw shell.

However the button 3 is formed, I pierce it axially by a hole having a diameter only 35 slightly in excess of that of the pigtail wire 5, so that when the latter is skinned of its insulating covering 6 and passed through the hole in the button, the wire substantially obstructs the hole. The length of the bared

40 wire end is so predetermined that when the wire is passed through the button the insulating cover 6 forms a shoulder 7 which abuts against the outer face of the button.

A slight recess 9 formed in the inner face 45 of the button around the hole, confines the solder drop 8 to central position. The length of the bared wire end is preferably sufficient to pass through the button and project slightly from its inner face.

When so positioned the wire may be secured by a drop of solder 8 applied to the projecting end of the wire, the solder overlying the inner face 50 of the button to form not only an anchor for

the pigtail, but also the center contact of the socket.

If desired, the projecting end of the wire may be offset over the inner face of the button to increase the security of its anchorage,

but this is not essential. In either case, the shoulder 7 serves not only as a closure which

prevents the escape of solder through the hole during the soldering operation, but also

as an abutment which prevents unseating of the center contact solder drop 8 by inward thrust upon the wire.

The bared end of the other pig tail 10 may

be solder at 11 to the base flange in the screw shell 4. When the pigtails have been thus

connected, the parts are mounted in the pre-formed insulating socket casing 12 and se-

cured therein in any suitable fashion. I have indicated the lip of the casing 12

pressed over the flared lip 13 of the screw shell 4, for this purpose.

My invention eliminates the expense of 75 the usual metallic center contact piece and the operation of rivetting the same to the button 3. This has the advantage not only

of economy of material and labor, but also reduces loss from breakage incident to the 80 rivetting operation. There could be no better electrical connection than that afforded by my invention, while its mechanical se-

curity is ample for this type of socket.

The construction which I have shown in 85 the drawings is the most economical, and is sufficient for this purpose. It would of

course be possible to slip a washer of metal or insulation over the bared wire end 5, so

that the washer rather than the wire insu-

lation itself forms the immediate closure at the outer end of the wire hole in the but-

ton 3. Or the bared wire end could be kinked to form the abutment shoulder. These and other expedients which will readi-

ly occur to those dealing with the construc-

tion, do not depart from the underlying thoughts which I claim as my invention.

I claim—

1. A lamp socket comprising a screw shell 100 contact, an insulating button secured there- to and pierced within the boundaries of the shell, in combination with a lead wire hav- ing an insulating jacket, the end of the wire being bared, said bared end of the wire pass- 105 ing into the hole in the button and its insu-

lating jacket forming a shoulder which bears against the outer face of the latter, together with solder engaging the bared end of the wire to mechanically and electrically connect 5 the same, said solder overlying the inner face of the button and forming the center contact of the socket.

2. The combination with a pierced insulating body, of a bared wire passing through 10 the hole in said body, an insulating jacket for said wire forming a shoulder abutting against the opposite face of the body to limit the displacement of the wire in the hole, together with solder engaging the projecting 15 wire end to mechanically secure the wire to the insulating body and to afford an exposed contact.

3. The method of forming and securing contact on an insulating body, which comprises forming a hole in an insulating body, 20 passing the bared end of an insulation-jacketed wire into the hole until halted by the end of the insulating jacket, and forming a contact by solder applied to the bared wire 25 end and overlying the surface of the insu-

lating body whereby said contact is secured in position by its engagement with the bared wire end and held against substantial displacement by the engagement of the wire jacket with the opposite face of the insulating body. 30

4. The combination with a pierced insulating body, of a bared wire end passing through the hole in the body, means limiting the insertion of the wire through said 35 hole, together with solder engaging the projecting wire end to mechanically secure the wire to the insulating body and to afford an exposed contact.

5. The combination with a pierced insulating body, of a bared wire entering the hole in said body, means limiting the entry of the wire into said hole, solder engaging the inserted end of the wire from the opposite 40 face of the body and serving not only to mechanically secure the wire to the body, but also to afford an exposed contact. 45

In testimony whereof I have signed my name to this specification.

GILBERT W. GOODRIDGE.
